Primary Examiner — Shannon W Morgan*Assistant Examiner* — Altaira J Swangin(74) Attorney, Agent, or Firm — Law Offices of Steven W. Weinrieb(57) CLAIM

The ornamental design for a hair curler, as shown and described.

DESCRIPTION

FIG. 1 is a first perspective view of a hair curler showing my new design;

FIG. 2 is a second perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken lines in the drawings illustrate portions of the hair curler which form no part of the claimed design.

1 Claim, 8 Drawing Sheets(56)
